UNITED STATES PATENT OFFICE.

HARRY H. BARBER, OF AURORA, ILLINOIS, ASSIGNOR TO BARBER-GREENE COMPANY, OF AURORA, ILLINOIS, A CORPORATION OF ILLINOIS.

CONVEYER TRUCK.

Application filed April 15, 1927. Serial No. 183,939.

This invention relates to a truck conveyer of that type which is adapted for receiving material at one end and conveying it to a higher elevation.

5 It is among the objects of this invention to provide such a conveyer in which the lower end of the boom may be positioned at a predetermined point, for example, under a coal car for conveying the coal therefrom to a 10 higher elevation, in which the inclination of the boom may be varied without a displacement of the lower end and in which the variation in the inclination of the boom does not affect the driving relation between the power 15 means and the conveyer on the boom.

In its broadest aspect, this invention consists of a conveyer boom mounted upon a support which is so connected to the boom as to be movably responsive to variations in the 20 inclination of the boom, for maintaining the lower end thereof at a predetermined point, and in which the driving mechanism for the conveyer on the boom is likewise responsive to variations in the inclination of the boom 25 for maintaining an effective drive for all inclinations of the boom.

The objects of the invention are preferably accomplished by the use of a rolling and 30 pivotal support, which is so connected to the boom that any variations in the inclination of the latter is adapted to roll and tilt the support.

With these and other objects in view which will become apparent in the following description and disclosures, this invention comprises the novel structure and combinations of parts hereinafter described and more particularly pointed out and defined in the appended claims.

40 In the accompanying drawings, which illustrate a preferred embodiment of this invention, and in which similar reference numerals refer to similar features in the different views:

45 Figure 1 is a side elevational view of a truck conveyer involving this invention, showing in dotted lines the position of parts when the boom is in its lowered position on the truck.

Figure 2 is an enlarged fragmentary side 50 elevational view of the truck conveyer showing in dotted lines the position of parts when the boom is in lowered position.

Figure 3 is an enlarged rear elevational view of the truck conveyer.

55 Figure 4 is a sectional view taken substan-

tially upon the line IV—IV of Figure 3 showing in dotted lines, the rolling supports in transversely adjusted positions.

Figure 5 is an enlarged sectional view upon the line V—V of Figure 3.

60 Figure 6 is an enlarged sectional view upon the line VI—VI of Figure 4 looking in the direction of the arrow and showing parts in elevation.

Figure 7 is an enlarged part sectional and 65 part plan view of the reversing drive for raising and lowering the boom.

Figure 8 is a view taken upon the line VIII—VIII of Figure 7.

Figure 9 is an enlarged sectional view 70 taken substantially upon the line IX—IX of Figure 1.

Figure 10 is an enlarged sectional view taken substantially upon the line X—X of 75 Figure 3.

Figure 11 is an enlarged sectional view taken upon the line XI—XI of Figure 5.

As shown on the drawings:

In the illustrated embodiment of this invention, the aforementioned pivotal and rolling support consists of a transverse member 1, to each end of which a rolling element in the form of a wheel 2 is swiveled by means of a suitable knuckle joint 3, as shown more clearly in Figure 10. The support further comprises a motor platform 4 and upright members 5, which in connection with the member 1 form a substantially bifurcated structure or standard for receiving the conveyer boom 6. This structure affords a movable or shiftable 90 fulcrum member for the boom, in that the same is supported thereby in inclined position as shown in Figure 1. To this end, a cable pulley 7 is journaled on the upper end of each side member 5. A cable 8 is trained over each pulley 7 and over a grooved roller 9. The rollers 9 are secured upon the ends of a shaft 10 which is secured to the bottom of the conveyer boom by means of suitable bearings 11 as shown in Figure 3. As the cables 8 pass over the rollers 9, they are anchored to suitable hasps 10^a on the side members 5 as shown in Figure 2. These cables extend downwardly, one passing under a guide roll 12 on the transverse member 1 and around a drum 13 shown more clearly in Figure 4. The other cable 8 passes around a coaxially arranged drum 14. It will, of course, be understood that the ends of the cables 8 will be finally attached to their re-

60

spective drums. The drums 13 and 14 are secured upon the ends of a short shaft 15 which is journaled in a suitable casing 16 on the base support 1. A worm gear 17 is keyed 5 upon the shaft 15. This worm gear is adapted to be driven by a worm 18 which is secured upon a shaft 19 which is coupled by means of a universal joint 20 (Figure 3) to a vertical shaft 21. The upper end of the vertical shaft 10 21 is provided with a pinion 22 adapted to be driven by either of the pinions 23 or 24 secured upon a short transverse shaft 25.

It will be noted with reference to Figure 3 that one upright member 5 is reinforced by 15 a sloping upright member 5^a, which extends from the transverse member 1 to the top of said member 5. The other transverse member is reinforced by an upright member 5^b, which extends in parallel relation to its member 5 to a point above the shaft 25, at which point there is a sloping brace 5^c, that connects with the member 5 and the adjacent member 5^b. The upright members are also reinforced by the bowed struts 5^d which lie in the same 20 longitudinal plane as the members 5. The aforementioned upright shaft 21 is journaled in a bearing 26 which is slidably mounted upon an upper flanged transverse brace 27 extending between the members 5 and 5^b. To 25 this end, the bearing 26 is provided with a flange 28 that rests upon the upper flanged transverse member 27. The flange 28 is provided with slots 29, for receiving studs 30, extending from the flange of the upper flanged 30 transverse brace 27. The bearing member 26 is provided with suitable ears 31 to which a link 32 is connected. The outer end of this link 32 is connected to a crank on a rod 33 which is rotatably held upon the upright 5^b 35 by means of suitable clips 34. The lower end of the rod 33 is provided with a handle 35, by means of which it may be operated for shifting the bearing 26 and the upper end of shaft 21.

40 Suitable power means are supported upon the platform 4 for driving the shaft 25. In the present instance, the power means consists of a gasoline engine 36 provided with a shaft 37 (Figure 2). The shaft 37 is 45 equipped with a sprocket gear 38 which is geared to a sprocket 39 on the shaft 25 by means of a suitable sprocket chain 40. The sprocket wheel 39 is provided with a clutch hub 41 which is loosely mounted on the shaft 50 55 25 and is adapted to be clutched thereto by a suitable clutch member 42. The shaft 25 is the main driving shaft of the machine, as will later more fully appear.

55 The boom is connected to the upright support by suitable link members upon each side thereof. A pair of links 43 which act as radius rods are pivotally connected at their forward ends to the lower portion of the conveyer boom, by means of a rod 44. The rear 60 65 ends of the bars 43 are suitably pivoted upon

the transverse member 1 in order that said bars may pivot or swing with respect thereto. Toward the upper end of the boom there is secured a transverse shaft 45, the ends of which project beyond the sides of the boom as 70 indicated in Figure 9. A link 46 is pivoted at one end to one end of the shaft 45. The other end of this link 46 is suitably pivoted to the upright support upon an axis 47 which is coincident with the axis of the main driving 75 shaft 25. Upon the opposite side of the boom a second link 48 is pivotally attached at its upper end to the shaft 45. This link 48 is provided with diverging arms, the lower ends of which are secured in rotatable sockets 49 80 (Figures 3, 5 and 11) which are respectively secured upon the uprights 5 and 5^b. It will be noted that these sockets have circular slotted portions 50, which extend around a bearing 51, in which the aforementioned shaft 25 is journaled, consequently, the lower pivot points of the rod 48 lie in the axis of the shaft 25. These bearings are attached to the upright members 5 and 5^a by means of U-shaped 85 bolts 52. A form of cam member 53 is 90 slipped over the ends of the U-shaped bolt and extends through the slot of the circular part 50 of the socket member 49 for maintaining the parts in proper assembly.

95 The boom 6, which may be of any suitable construction, preferably consists of spaced upper and lower angle members 54 which are connected by metal lattice work 55. A lower series of rolls 56 is supported from the lower angle members and series of rolls 57, 58 and 59 (Figure 9) are supported upon the upper angle members 54. The upper rolls are preferably supported in a casting 60 which is provided with spaced arms 61 for receiving the pintles of the rolls, which are arranged in 100 dish-shaped relation. The upper and lower series of rolls support an endless conveyer 62 which may be of any convenient design. This conveyer passes over suitable terminal pulleys 63 at the ends of the boom. The upper pulley 63 is geared by suitable sprocket gearing 64 to the shaft 45 and the shaft 45 is geared by suitable sprocket gearing 65 to the main driving shaft 25 which is provided with a suitable sprocket gear 66 loosely mounted upon the shaft 25 but adapted to be connected therewith by means of jaw clutch member 67 105 engaging the jaws on the hub of said sprocket. The clutch member 67 is provided with a groove 68 for engaging a bell crank shifter lever 69 to which a link 70 is connected by means of which the bell crank may be operated for disengaging or engaging the clutch. It will be noted that the link 48 and the companion link 46 connect the axis of the sprocket 66 and the sprocket 71 of the aforementioned sprocket gearing 65 on the shaft 45. Consequently, the two driven members 66 and 71 are always spaced a constant distance irrespective of the inclination of the boom. 110 115 120 125 130

In the operation of this conveyer it is adapted to be manually moved in position. If it is desired to unload a car of coal, the lower end of the boom will be placed beneath the discharge hopper of the car. This boom may extend for 40 feet or more to a truck or coal bin or the like for transferring the coal thereto. In order that the discharge end of the boom may be at the proper elevation for the truck or bin or the like it may be raised or lowered. When it is desired to raise or lower the boom, the clutch member 67 is preferably disconnected from the sprocket drive and the rod 33 is operated for shifting the gear 22 into engagement with one of the pinions 23 or 24 according to whether it is desired to raise or lower the boom. If the engine is then started, the rotation of the shaft 25 will rotate the vertical shaft 21 for rotating the drums 13 and 14 in the proper direction for lowering or raising the boom. During the raising and lowering of the boom the connecting links 43, 46, and 48 will tend to tilt the boom support as shown in dotted lines in Figures 1 and 2.

If the rolling support for the boom is maintained stationary during the raising or lowering of the boom, the front end of the boom will naturally change its position as shown in Figure 1; however, the front end of the boom may be anchored in a predetermined position. In such case, the supporting standard for the boom will not only tilt as shown in the drawing, but will also be compelled to move upon the rolling elements 2 when the inclination of the boom is varied. The link members 43 and 46 act substantially as a couple and cause a movement of the boom support.

It will be appreciated that during all adjustments of the boom, the driving shaft 37 of the engine, and the main driving shaft 25, will be spaced a constant distance. Likewise, the driving member 71 and the sprocket 66 will remain at a constant distance. While it is necessary that the supporting frame of the boom shift during a change in the inclination of the boom, this shifting does not in any way affect the driving relation between the conveyer and the engine.

It will further be appreciated that in the use of this conveyer it is possible to position the feeding end of the conveyer at any predetermined desired point, and it is possible to vary the inclination of the conveyer without disturbing the feeding end of the conveyer. It is also possible to turn the wheels 2 transversely and roll the boom to change the position of the discharge end without materially changing the location of the lower end.

It will also be appreciated that during any such variations in the inclination of the boom, the drive between the conveyer and engine remains unaffected. This is of course due to the fact that the driving members have

a fixed relation, irrespective of the position to which they may be adjusted or moved through the raising or lowering of the boom. Not only is the support for the boom movably responsive to the inclination of the boom, 70 the driving mechanism for the conveyer is likewise responsive to the same movements. Consequently, the conveyer drive is never affected by any change in the position of parts.

I am aware that many changes may be 75 made and numerous details of construction may be varied through a wide range without departing from the principles of my invention and I, therefore, do not propose limiting the patent granted hereon, otherwise than 80 necessitated by the prior art.

I claim as my invention:

1. In a conveyer truck, a rolling and tilt-able support, a conveyer boom, and opposed members pivotally connecting said boom with 85 vertically spaced points on said support.

2. In a conveyer truck, a rolling and tilt-able support, a conveyer boom, opposed members pivotally connecting said boom with vertically spaced points on said sup- 90 port, a conveyer on said boom, and power means on said support connected to said conveyer.

3. In a device of the class described, a roll- 95 ing and tilttable support, a boom, opposed members pivotally connecting said boom with vertically spaced points on said sup- port, power means on said support, a con-veyer on said boom, driving mechanism be-tween said power means and conveyer com- 100 prising a pair of driven elements, one located at each pivot point of one of said members.

4. In a conveyer truck, an inclined boom adapted to have its lower end located at a predetermined point, a support, opposed 105 members pivotally connecting said boom with vertically spaced points upon said support, means for raising and lowering said boom, said support being movably responsive during the raising and lowering of said boom 110 for maintaining said lower end at said pre-determined point, a conveyer on said boom, and driving mechanism for said conveyer movably responsive to variations in the in- 115 clination of the boom for maintaining an effective drive for all inclinations of the boom.

5. In a conveyer truck, an inclined boom adapted to have its lower end located at a predetermined point, a support, opposed link 120 members connecting said boom and support, means for varying the inclination of the boom, a conveyer on said boom, a driving mechanism on said support and connected to said boom, said support and driving mecha- 125 nism being movably responsive to variations in the inclinations of said boom for the purpose set forth.

6. In a conveyer truck, a pivotal and roll- 130 ing bifurcated standard, a boom located in

the bifurcation of said standard, opposed link members pivotally connecting said boom with vertically spaced points on said standard, power operated means on said standard for varying the inclination of the boom, a conveyer on said boom, and power operated means unaffected by changes in the inclination of said boom for operating said conveyer.

7. Mechanism for supporting and driving a conveyer at various inclinations with one end located at a predetermined point, comprising a support, opposed members connecting said boom with vertically spaced points upon said support, driving mechanism on said support connected to said conveyer, said support and driving mechanism being movably responsive to changes in the inclination of the boom for the purpose set forth.

8. In a conveyer truck, a rolling and pivotal standard, a conveyer boom, opposed members pivotally connecting said boom with vertically spaced points on said standard, power operated means on said standard for raising and lowering said boom for varying its inclination, said opposed members tending to tilt and roll said standard during the raising and lowering of said boom.

9. In a conveyer truck, a movable standard, a conveyer boom, opposed members pivotally connecting said boom with vertically spaced points on said standard, means on said standard for raising and lowering said boom for varying its inclination, said members adapted to cause a movement of said standard during the raising and lowering of said boom.

10. In a conveyer truck, a longitudinally and transversely rolling bifurcated standard, a conveyer boom supported in the bifurcation of said standard, a pair of links pivotally connecting said boom with lower points on said standard, a pair of links pivotally connecting upper points of said standard with said boom in opposed relation to said first mentioned links, a conveyer on said boom, power means on said support, and driving connections between said power means and conveyer comprising a pair of driven elements located at the pivot points of one pair of links.

50 11. In a conveyer truck, a longitudinally and transversely rolling bifurcated standard adapted for tilting movements, a conveyer boom supported in the bifurcation of said standard, power means on said standard for raising and lowering said boom, opposed links pivotally connecting said boom with upper and lower points on said standard, said

links being effective for causing a tilting of said standard during the raising and lowering of said boom, a conveyer on said boom, and driving connections between said power means and conveyer unaffected by the tilting movements of said standard.

12. In a conveyer truck, a bifurcated standard, a two wheeled support pivotally connected to said standard, a boom supported by said standard, opposed links pivotally connecting said boom with upper and lower points on said standard, power operated means on said standard for raising and lowering said boom, said links being effective for causing a tilting of said standard during the raising and lowering of said boom, an endless conveyer carried by said booms, and a driving connection between said power means and conveyer unaffected by the tilting movements of said standard.

13. In a conveyer truck, a bifurcated standard, transversely adjustable wheels pivotally supporting said standard, a boom in the bifurcation of said standard, opposed links pivotally connecting said boom with upper and lower points on said standard, a conveyer on said boom, power means on said standard, driving means between said power means and conveyer comprising a pair of driven elements located at the pivot points of one of said links, and mechanism driven by said power means for raising and lowering said boom.

14. In a conveyer, a truck including a tiltable bifurcated standard, a boom in the bifurcation of said standard, cable means for raising and lowering said boom, and opposed vertically spaced braces connecting said boom and truck, said braces causing a tilting of said standard during the elevation or lowering of said boom.

15. In a conveyer, a truck including a tiltable standard, a boom, cable means for supporting said boom upon said standard for elevating and lowering movements, a brace extending from the lower part of said truck and pivotally connected to said boom, and a second brace extending in opposed relation to said first brace and pivotally connecting the upper part of said boom with said standard and effective for causing a tilting of said standard during the raising and lowering of said boom.

In testimony whereof I have hereunto subscribed my name at Aurora, Kane County, Illinois.

HARRY H. BARBER,
